UNITED STATES PATENT OFFICE.

CHARLES A. CLARK, OF HARTFORD, CONNECTICUT.

SNAP-SWITCH-OPERATING MECHANISM.

SPECIFICATION forming part of Letters Patent No. 737,349, dated August 25, 1903.

Application filed July 23, 1902. Renewed July 8, 1903. Serial No. 164,753. (No model.)

To all whom it may concern:

Be it known that I, CHARLES A. CLARK, a citizen of the United States, residing at Hartford, in the county of Hartford and State of Connecticut, have invented certain new and useful Improvements in Snap-Switch-Operating Mechanism, of which the following is a specification.

This invention relates to the mechanism in a rotary snap-switch which holds the rotary parts against movement until the spring has been given the necessary tension to throw the parts quickly.

The object is to provide a simple, compact, and durable mechanism for this purpose which is cheap to manufacture and sure in action.

In this mechanism the handle-spindle has fixed gear and a loose disk connected with the rotatory poles, which disk carries two pinions that mesh with the gear and have detents arranged to engage with and be disengaged from teeth of a circular ratchet secured to the base of the switch as the spindle is turned for making the spring tense.

Figure 1 of the accompanying drawings shows a plan of a switch having this operating mechanism, with the handle and cover of the switch omitted. Fig. 2 shows a plan of the circular ratchet on the base of the switch. Fig. 3 shows on enlarged scale a view of the under side of the loose spindle-disk with the detents and pinions engaging the spindle-gear. Fig. 4 shows a view of the under side of the loose spindle-disk with the detents engaging the fixed ratchet, and Fig. 5 shows an elevation of the operating mechanism on the spindle with parts cut in section.

The base 1 of the switch is made any common shape, of insulating material, and is provided with stationary terminal contacts 2, as usual. In an opening in the center of the base is a bushing with a circular ratchet 3, fixed to its upper end. Supported by the bushing is the spindle 4, which has a handle 5 and a throwing-spring 6. The sleeve 7 is loose on the spindle. One end of the throwing-spring is fastened to a collar on the spindle and the other end is fastened to the disk on the spindle. A gear 9 is attached to or formed a part of the spindle, and attached to or formed

a part of the sleeve on the spindle is a disk 10. In a recess in the under side of the disk are two pinions 11. These pinions are held in position by a band 12, so as to mesh with the gear. Fastened to or formed a part of each pinion is a detent 13. The rotary poles 14 are attached to the disk in a common manner. The sleeve and disk, with the pinions, detents, and rotatory poles, are placed on the spindle, so that the spindle-gear meshes with the disk-pinions. Then the spindle is placed in the bushing in the base, so that the pinion-detents engage with the teeth of the fixed circular ratchet. When the handle is turned, the spring is tightened, and the gear on the spindle turns the pinions and moves the detents out of engagement with the ratchet-teeth. The parts are so timed that the spring is made quite tense before the detents are released from the ratchet-teeth in order that the poles be thrown quickly, when the disengagement of the detents from the ratchet-teeth is complete. The movement of the disk with relation to the spindle under the impulse of the spring as the poles are thrown causes the pinions to turn back the detents, so that they will engage the next teeth of the ratchet and hold the poles until the handle is again turned. The detents are moved positively into and out of engagement with the ratchet teeth by the gear and pinions, so that this mechanism is sure in action. The detents and the ratchet-teeth are strong, and the blow incident to the stopping of the poles by the engagement of the detents with the ratchet-teeth is on each side of the spindle in line directly across the strong detents, so that there is little liability of the parts becoming broken or worn into an inoperative condition. These parts are cheap to make and easy to assemble.

I claim as my invention—

1. An electric snap-switch having a base with a fixed circular ratchet, a handle-spindle with a fixed gear and a loose disk, said disk carrying pinions in mesh with the gear with detents fixed to the pinions and engaging the ratchet-teeth, and a spring with one end connected with the handle-spindle and the other end connected with the disk, substantially as specified.

2. An electric snap-switch having a base

with a central bushing and a fixed circular ratchet attached to the bushing, a handle-spindle supported by the bushing and having a fixed gear and a loose sleeve with a disk carrying pinions that mesh with the gear and have detents engaging the ratchet-teeth, and a spring with one end connected with the spindle

and the other end connected with the sleeve, substantially as specified.

CHARLES A. CLARK.
